(57) **CLAIM**

We claim the ornamental design for a lamp, as shown and described.

DESCRIPTION

FIG. 1 is a front view of the lamp showing our new design; FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is another perspective view of the lamp in a tilted state.

The broken lines shown in the drawings illustrate portions of the article that form no part of the claimed design.

1 Claim, 4 Drawing Sheets
